[57] CLAIM

The ornamental design for a logsplitting apparatus, as shown and described.

DESCRIPTION

FIG. 1 is a bottom plan view of the novel logsplitting apparatus;

FIG. 2 is a top plan view thereof;

FIG. 3 is a side elevational view thereof, the opposite side view being a mirror image thereof;

FIG. 4 is a front elevational view thereof; and,

FIG. 5 is a rear elevational view thereof.

The broken line showing is for illustrative purposes only and forms no part of the claimed design.
